UNITED STATES PATENT OFFICE.

ALEXANDER THOMAS TERRY, OF TALCOTT, WEST VIRGINIA.

DESIGN FOR A RAILROAD-RAIL BRACE.

SPECIFICATION forming part of Design No. 26,113, dated September 29, 1896.

Application filed August 19, 1896. Serial No. 603,275. Term of patent 3 years.

To all whom it may concern:

Be it known that I, ALEXANDER THOMAS TERRY, a citizen of the United States, residing at Talcott, in the county of Summers and State of West Virginia, have invented and produced a certain new and original Design for a Railroad-Rail Brace; and I do declare the following to be a full, clear, and exact description of the invention, such as will enable others skilled in the art to which it appertains to make and use the same.

My invention has relation to a design for railway track or rail braces.

It relates to the construction of the brace, and especially to a brace constructed of wrought metal.

My invention relates particularly to the rail or track brace, as illustrated in the accompanying drawing, in which—

The figure represents a perspective view of a railway-rail brace embodying my design.

The leading features of my design appear in the following description:

The brace is approximately rectangular in shape, and comprises the flat body portion 1, 25 the right-angular shoulders 2 2, the raised end portions 3 3, and the integral right-angular ribs 4 4. A series of perforations 5 5 or bolt-holes extend through the body portion 1 and the raised end portions 3 3. 30

Having thus described my design, what I claim as new, and desire to secure by Letters Patent of the United States, is—

The design for a railway rail or track brace, substantially as herein shown and described. 35

In testimony whereof I hereunto affix my signature in presence of two witnesses.

ALEXANDER THOMAS TERRY.
